UNITED STATES PATENT OFFICE.

ALBERT ROMINGER, OF CAPAY, CALIFORNIA.

POWER-INCREASING DEVICE FOR TRACTOR-MOTORS.

1,178,105.

Specification of Letters Patent.

Patented Apr. 4, 1916.

Application filed October 18, 1915. Serial No. 56,561.

To all whom it may concern:

Be it known that I, ALBERT ROMINGER, a citizen of the United States, residing at Capay, in the county of Yolo, State of California, have invented certain new and useful Improvements in Power-Increasing Devices for Tractor-Motors; and I do declare the following to be a full, clear, and exact description of the same, reference being had 10 to the accompanying drawings and to the characters of reference marked thereon, which for a part of this application.

This invention relates to an attachment for the motors of motor vehicles, especially 15 those used in connection with tractors having speed governors, for maintaining a maximum speed of the motors under ordinary circumstances, the object of the invention being to produce an attachment for the control 20 lever of the throttle of the motor whereby, when required, the speed and power on the motor may be forced against the action of the governor. It often happens that in certain stress of circumstances more power 25 is required of the motor than is allowed by the speed governor and my invention allows of this power being called into action when desired.

A further object of the invention is to 30 produce a simple and inexpensive device and yet one which will be exceedingly effective for the purposes for which it is designed.

These objects I accomplish by means of such structure and relative arrangement of 35 parts as will fully appear by a perusal of the following specification and claims.

In the drawings similar characters of reference indicate corresponding parts in the several views.

40 Figure 1 is an outline view of a motor showing my improved attachment thereon. Fig. 2 is an end view of my improved attachment.

Referring now more particularly to the 45 characters of reference on the drawings, the numeral 1 designates the steering post of the vehicle, the numeral 2 the throttle control rod thereon operating the finger member 3 which finger member is connected by a 50 link 4 with my improved attachment 5 which consists primarily of a bell crank pivotally mounted at 5^a and having a pair of projecting arms 8 and 10 spaced apart. The arm 8 terminates in an eye which fits over 55 the throttle lever 6 of the carbureter 7 and the member 10 terminates in a bifurcated

yoke which straddles the throttle lever 6, the members 8 and 10 being spaced apart as noted. A collar 9 is secured by a setscrew or other suitable means to the throttle lever 6 between the members 8 and 10. The lever 6 projects through the end of the governor lever 15 and is provided with a collar 12 and with a spring 13 interposed between the governor lever 15 and collar 12. 60 The governor lever 15 is connected by the rod 16 with the governor 17 in the usual manner. When the motor is started and the throttle lever advanced, it moves the member 8 away from the collar 9 which allows 65 the throttle to open up to any desired degree under the impetus of the governor. When the limit of speed of the motor, as controlled by the governor is reached, then the action of the member 8 would be of no 70 avail, and the motor would be held at its fixed speed by the governor unless something was provided for forcing the governor and opening the throttle, and this I accomplish by means of the member 10 which can 75 be moved against the collar 9 to force the rod 6 ahead and pull on the lever 15 and force the governor 17 to allow of a greater speed of the motor due to the greater open 80 position of the carbureter 7. 85

In the now commonly used control means for throttles, the bell crank 5 is provided with one arm against which a collar acts as the carbureter opens and when the one arm has reached the limit of movement, as 90 determined by the speed of the motor, there is no way of forcing the same to get greater speed or power in emergencies and it is this emergency use which I provide for by the use of the arm 10. 95

From the foregoing description it can readily be seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention. 100 105

Having thus described my invention what I claim as new and useful and desire to secure by Letters Patent is:

1. A device of the character described comprising the combination with the throttle lever of a carbureter and a governor connected with the throttle lever, of a stop 110

member on the lever, a bell crank pivotally mounted independently of the lever and having a pair of arms, one projecting on each side of said stop member in spaced relation, and means for operating the bell crank, as described.

2. A device of the character described comprising the combination with the throttle lever of a carburetor arranged to move under spring pressure and a governor connected with the throttle lever, of two members op-

erable by a common lever, one member arranged to retard the movement of the rod under the spring pressure, and the other arranged to force such movement, as de- 15 scribed.

In testimony whereof I affix my signature in presence of two witnesses.

ALBERT ROMINGER.
